DESIGN FOR A SWEATER ENSEMBLE

Sam Levine, New York, N. Y.

Application April 28, 1938, Serial No. 76,778

Term of patent 3½ years

To all whom it may concern:

Be it known that I, Sam Levine, a citizen of the United States of America, residing in city of New York, county of New York, and State of New York, have invented a new, original, and ornamental Design for a Sweater Ensemble, of which the following is a specification, reference being had to the accompanying drawing, forming part thereof,

Fig. 1 is a front view of a sweater ensemble showing my new design.

Fig. 2 is a front view of the sweater portion of the ensemble.

Fig. 3 is a rear view of Fig. 2.

The rear view of the sweater ensemble is conventional.

My design is characterized by the specific neckline on the front coat portion of the sweater ensemble as shown.

I claim:

The ornamental design for a sweater ensemble substantially as shown and described.

SAM LEVINE.
